UNITED STATES PATENT OFFICE.

LEE C. HALBIN, OF MURPHYSBORO, ILLINOIS.

SAFETY DEVICE FOR ELEVATORS.

Application filed December 26, 1922. Serial No. 609,016.

To all whom it may concern:

Be it known that I, LEE C. HALBIN, a citizen of the United States, residing at Murphysboro, in the county of Jackson, 5 State of Illinois, have invented certain new and useful Improvements in Safety Devices for Elevators; and I do hereby declare the following to be a full, clear, and exact description of the invention, such as will enable others skilled in the art to which it appertains to make and use the same.

This invention relates to new and useful improvements in safety devices and particularly to safety devices for elevators.

One object of the present invention is to provide a novel and improved mechanism which will automatically grip the uprights of the elevator shaft and stop the elevator car within a short space, whereby the car 20 is effectively prevented from dropping to the bottom of the shaft.

Another object is to provide a novel and improved device of this character which is simple in construction, positive in operation, 25 and which can be readily and easily installed in elevators now in use.

Other objects and advantages will be apparent from the following description when taken in connection with the accompanying 30 drawing.

In the drawing:

Figure 1 is an elevation of an elevator car and portions of the shaft, showing the safety device in normal inoperative position.

Figure 2 is a similar view showing the device in operative position.

Figure 3 is a top plan view of the car, the uprights of the shaft being horizontally sectioned.

Figure 4 is a side elevation of the elevator car and portion of the shaft showing the safety cams which engage with the upright, the dotted position showing the cams engaged with the upright.

Figure 5 is a vertical sectional view through the upper portion of the car and the upright engaging gears, on the line 5—5 of Figure 3.

Referring particularly to the accompanying drawings, 10 represents the uprights of the shaft on the inner face of each of which is formed or secured a longitudinal toothed rack 11. Slidable vertically between these uprights is the elevator car which includes 15 the platform or floor 12, the uprights 13, and the upper transverse beam 14 connected

to the upper ends of the uprights 13. Mounted on the outer face of the upper end of each of the uprights 13 is an angular U-shaped guide 15 which engages with the adjacent upright 10 of the shaft and holds the car against rocking movement. Similar guides 16 are carried by the lower portions of the uprights 13, also engaging with the uprights 10. Braces 17 extend from the upper ends of the uprights 13 to the corners of the floor of the car. The type of car and shaft herein illustrated is such as is used in mines, but it should be understood that the application of the present invention is 70 equally applicable to other types of elevators.

Upwardly extending loop guides 18 are carried by the transverse beam 14, and slideable on the beam, longitudinally thereof, and within the guides, are the bars 19, each having on its outer end the bearings 20 which support the shaft 21. On the shaft 21, between the bearings, is a toothed wheel 22 which is adapted to engage with the rack 11, when the bar is moved outwardly, as will be more clearly explained hereinafter. Secured to the inner end of one of the bars 19 is a toothed rack bar 23 the teeth of which are arranged to be engaged by a pawl 24 carried by the inner end of the other bar 19, whereby the bars 19 can be adjusted toward and away from each other, according to the width of the elevator shaft with which the invention is used. A bowed spring 25 extends between the bars 19 and has its ends secured thereto, the intermediate portion of the spring having the cable 26 secured to and extending upwardly therefrom. This cable is the lifting and lowering cable for the car, as will be readily understood. It will be noted that when the weight of the car is on the cable 26, the spring 25 is bowed upwardly to a greater extent, with the result that the bars 19 are 100 withdrawn so that the pinions 22 are out of engagement with the racks 11. This is the normal condition of the parts when the elevator is in operation, but should the cable 26 break, the spring 25 would automatically 105 resume its normal flat, or partially flat, condition and push the bars outwardly so that the pinions 22 would engage with the teeth of the racks 11 and be rotated thereby.

The shafts 21 extend short distances from opposite sides of the beam 14 and have the peripheral flanges 27 thereon, whereby 110

winding drums are provided, and to which are secured the ends of cables 28. Mounted in brackets 29, on the bottom of the car, and arranged to engage with two opposite vertical faces of each upright 10, are the pivoted cams 30, said cams being normally held out of contact with the uprights by the springs 31. The other ends of the cables 28 are each connected to a cam 30, so that 10 when the shafts 21 are rotated by engagement of the pinions 22 with the racks 11, the cams will be moved so as to engage with the uprights 10, when the weight of the car will cause the cams to bind tightly against 15 the uprights 10 and hold the car from movement downward.

In the opposite longer side faces of the bars 19 there are formed grooves 32 in which engage the inturned upper ends of 20 the plates 33 which are secured to the opposite sides of the uprights 13, and whereby the said bars are held in proper alignment when moved into and out of operative position.

25 It will thus be seen that should the cable 26 break and the car fall, the spring 25 would assume its normal flat condition and thus push the bars 19 outwardly so that the pinions 22 would engage with the racks 11, 30 and as the car moved downwardly in the shaft these pinions would rotate to wind the cables 28 on the shafts 21 and pull the cams 30 into engagement with the uprights 10, and thus bring the car to a stop.

35 Upon the weight of the car being again supported by the new cable which replaced the broken cable 26, the bars 19 would be withdrawn so that the pinions would not mesh with the racks and the springs 31 40 withdraw the cams from engagement with

the uprights 10. The car would then be restored to its normal condition, and operation thereof permitted.

45 Thus there is provided a novel and improved device for an elevator whereby danger of the car dropping to the bottom of the elevator shaft, with the usual disastrous results, effectively prevented.

What is claimed is:

1. The combination with the uprights of 50 an elevator shaft and the car thereof, of rack bars mounted on the uprights, transversely slideable members mounted on the car, pinions and associated winding drums mounted on and movable with the slideable 55 members, wedge gripping means on the car for engagement with the untoothed side faces of the uprights, and cables connected to the drums for winding thereon and to the wedge means.

2. The combination with an elevator car and the uprights of the elevator shaft, of 60 racks on the uprights, transversely and oppositely slideable bars on the car, shafts on the slideable bars, pinions and winding 65 drums on the shafts, the pinions being arranged to engage with and be rotated by the racks to rotate the drums, cams mounted on the car and arranged to engage with the opposite untoothed side faces of the uprights, and cables connected to and windable on the drums and connected to the cams.

70 In testimony whereof, I affix my signature, in the presence of two witnesses.

75 LEE C. HALBIN.
